UNITED STATES PATENT OFFICE.

CHARLES WALTER LUND, OF WILLOW, CALIFORNIA.

WHISTLE.

1,272,822.

Specification of Letters Patent. Patented July 16, 1918.

Application filed September 1, 1916. Serial No. 118,082.

To all whom it may concern:

Be it known that I, CHARLES WALTER LUND, a citizen of the United States, residing at Willow, in the county of Glenn 5 and State of California, have invented certain new and useful Improvements in Whistles; and I do declare the following to be a full, clear, and exact description of the invention, such as will enable others skilled 10 in the art to which it appertains to make and use the same.

This invention relates to improvements in signals, particularly whistles, and is designed for use in connection with automobiles, motor trucks, and other vehicles, and 15 boats.

The principal object of the invention is to provide a signal or alarm of this character in which the tone is automatically varied.

20 An additional object is to provide a whistle in combination with a double-acting pump whereby the alarm may be sounded on both strokes of the pump.

Still another object is to provide a very 25 simply constructed alarm which can be inexpensively manufactured and yet which will be very efficient in operation.

With the foregoing and many other objects in view, my invention resides in the 30 novel features of construction, combination and arrangement of parts which will be hereinafter more particularly described and claimed.

In the accompanying drawing: 35 Figure 1 represents a side elevation of an alarm constructed in accordance with my invention;

Fig. 2 is a central longitudinal section on the plane of the line 2—2 of Fig. 1; and

40 Figs. 3 and 4 are transverse sections taken respectively on the lines 3—3 and 4—4 of Fig. 1.

Referring more particularly to the drawing, wherein similar reference characters 45 designate like parts in all the views, the numeral 1 denotes a pump cylinder having flat ends 2, from one of which projects a tube 3, said tube being connected to the pump cylinder by any preferred means at the center 50 of one end 2. This tube forms the whistle portion of the alarm and has its outer end closed and provided with a mouth 4 as is usual in devices of this character. Surrounding the tube 3 is a horn-shaped mem- 55 ber 5 which serves to protect the whistle

and also give the device the appearance of an electric horn.

Within the pump cylinder 1 is placed the piston 6 used for supplying the compressed air for operating the whistle. This piston 60 is fixed intermediate the ends of the piston rod 7, the latter projecting through both the flat ends 2 as shown in Fig. 2. Suitable packing boxes 8 surround the openings in the ends 2 where the piston rod extends 65 therethrough so as to prevent the escape of air. One end of the piston rod has an operating means which will later be described connected thereto, while the opposite end extends into the tube 3 where it is provided 70 with an additional piston 9 which closely fits the walls of the latter and forms a movable end therefor.

It is well known that different tones of 75 whistles may be provided by using tubes of different lengths or different fluid capacities. Therefore in the present instance I obtain a great variety of tones by varying the length of the air chamber within the tube 3. This is accomplished by moving the piston 9 80 back and forth within the tube.

The piston 6 for compressing the air within the pump cylinder 1 may be operated by hand or by any other preferred means, but when the device is used on automobiles and 85 other vehicles the structure illustrated is ordinarily employed. This consists of an operating lever in the form of a handle 10 which is pivoted intermediate its ends to one end of the piston rod as shown at 11, this 90 end of the rod being preferably the one opposite the end on which the piston 9 is mounted. One end of the lever is pivoted to a link 12 which in turn is pivotally connected to an ear 13 formed on one end 2 of 95 the pump cylinder. From the drawing it will be seen that when this handle 10 is moved to cause the piston rod to reciprocate the piston 6 within the cylinder 1, it will cause the air contained therein to be compressed between either of the end walls 2.

In order to admit air to the cylinder, suitable check valves 14 are formed in each of the ends 2. The opposite ends of the cylinder are also provided with outlet ports 15 105 and 16, each of which communicates with a pipe 17, whereby the compressed air is fed from the pump to a point adjacent the mouth 4 of the whistle where it is discharged in such a manner that it will cause the whis- 110

tle to sound. The pipe 17 is provided with a double acting valve 18 which, when the piston 6 is moved in one direction, as for instance toward the rear end of the pump cylinder, will close the outlet port 16. When the piston is moved in the reverse direction this port 16 will be opened and the portion of the pipe leading from the port 15 closed. Thus a double acting pump is provided which supplies compressed air on both strokes of the piston.

Since the piston 9 is connected directly with the piston 6 it moves therewith, and thus the air chamber of the tube 3 is continuously changing in length. As hereinbefore pointed out this change in the length of the column of air in the tube causes the tone of the whistle to change. From the foregoing description it will be seen that I have invented a very simply constructed, yet novel signal which will be operated continuously and the tone thereof automatically changed during the movement of the operating parts.

I claim:

1. A whistle, a pump for supplying compressed fluid for operating the same, and means for simultaneously changing the size of the fluid chamber of said whistle with the movement of the piston of said pump.

2. In combination, a whistle, a pump for supplying compressed fluid for operating

the same, and a piston disposed in said whistle for changing the size of the fluid chamber and operatable simultaneously with the piston of the pump whereby to change the tone of the whistle.

3. In a device of the class described, a pump cylinder, a whistle connected thereto, a piston rod extending through said pump cylinder and into said whistle, a piston disposed intermediate the ends of said rod within said pump cylinder, an additional piston on said rod within said whistle and forming one end of the latter, and means for conveying compressed fluid from said pump cylinder to the whistle.

4. A whistle comprising a compressed air supply device, a whistle tube connected to said device, said tube having a mouth near the outer end thereof, a passageway extending along one side of said tube, across the outer end thereof, partway down the other side and provided with an outlet discharging directly into the mouth of said tube, and means of communication between said air supply device and said passageway.

In testimony whereof I have hereunto set my hand in the presence of two subscribing witnesses.

CHARLES WALTER LUND.
